UNITED STATES PATENT OFFICE

2,508,421

DUMPING CONTROL FOR SCRAPERS

Karl E. Reischl, South Milwaukee, Wis., assignor
to Bucyrus-Erie Company, South Milwaukee,
Wis., a corporation of Delaware

Application April 3, 1947, Serial No. 739,060

4 Claims. (Cl. 37—126)

1

My invention relates to new and useful improvements in wheeled scrapers of the general type shown and described in U. S. Patent No. 2,321,410, granted June 8, 1943, to George W. Mork et al., reference to which patent is hereby made, inasmuch as this present invention represents an improvement thereon.

In scrapers of that type, the scraper fills and dumps at its front end.

The main frame of such a scraper is pivoted at either its front end or rear end to a wheeled truck, and the digging and spreading depth is determined by raising or lowering the other end with respect to a second truck. This is the first operating function.

In Mork the pivoting is at the front end, and the raising and lowering takes place at the rear end. In my present invention I show pivoting at the rear end and raising and lowering at the front end, but this is not essential.

The digging blade is carried rigid with the main frame, though this is not essential.

Adjacent the digging blade is pivoted a dirt-extruding curved member, variously termed. For conformity with the nomenclature of the Mork patent, it will here be called a "bucket." Swinging this bucket upward to dump is the second function. Returning this bucket to load-carrying position is the third function.

There is also a front closure, known as the "apron." Opening this apron (when digging or dumping), and closing it again for carrying, is the fourth function.

Mork has two controls (ropes), one of which performs the first function (namely depth-control), and the other of which successively performs the fourth function (apron opening) and the second function (dumping). For the third function (bucket return), Mork depends on a kick-back cam, actuated by the fall of the apron.

It is the principal object of my present invention to employ two controls, one of which performs the first function (depth control), and the other of which performs the fourth function (apron opening), and to provide an interlock between the apron, the main frame and the bucket, whereby the opening of the apron will perform the second function (dumping) and the initial dumping movement of the bucket will be slow under a large applied hoisting force and the later dumping movement will be fast and with less applied force.

In addition to my principal object above stated, I have worked out a number of novel and useful details, which will be readily evident as the description progresses.

2

My invention consists in the novel parts and in the combination and arrangement thereof, which are defined in the appended claims, and of which two embodiments are exemplified in the accompanying drawings, which are herein-after particularly described and explained.

Throughout the description, the same reference number is applied to the same member or to similar members.

10 Figure 1 is a vertical longitudinal section of the first embodiment of my scraper in carrying position.

Figure 2 is a similar section of the same embodiment of my scraper with the apron alone partly raised in dumping position.

Figure 3 is a similar section of the first embodiment of my scraper with both apron and bucket raised in full dumping position.

Figure 4 is a rear end view of the first embodiment of my scraper taken along the line 4—4 of Figure 3.

Figure 5 is a vertical longitudinal section of the second embodiment of my scraper with both apron and bucket raised in full dumping position.

25 Referring now to Figures 1 to 3 we see that the implement to which I have applied my invention, includes a forward truck 21, and a rear truck 22, supported respectively on forward wheels 23 and rear wheels 24. The rear truck 22 is rigidly secured to two side plates 25, preferably having substantially the outline indicated in the figures. In place of either such truck, we could support one end of the scraper on the propelling vehicle.

These parts constitute parts of the frame of the implement, and are connected together in such a way as to enable the scraper blade 26, which is located forward of the bucket 27, to be raised or lowered at will with respect to the ground level. In order to accomplish this, the forward truck

40 21 is preferably provided with rigid rearwardly projecting side arms 28 that extend rearwardly to a point about midway between the two trucks, at which point the arms 28 are connected by pivot bolts or pins 29 to the side plates 25.

45 Rigidly secured to the side plates 25, I provide at the rear thereof a transverse lower beam 30, and an upper beam 31 and at the forward end thereof a transverse beam 32. The inclined scraper blade 26 is preferably rigidly secured to the side plates 25, and cuts into the earth when the bucket 27 is being filled. Adjacent the blade 26 and preferably at its rear edge, the bucket 27 is pivotally mounted on a transverse pivot bar 33.

When the bucket 27 is in the position of rest, as indicated in Figure 1, the stop-bracket 34, carried by the rear face of the bucket, rests

against a bumper or bumpers 35 on the top of lower beam 30, and this limits the downward movement of the bucket.

During the scraping operation the blade 26 is held at a low level so as to engage the dirt to be picked up, and the dirt passes over the blade into the bucket. As this takes place, an apron 37 at the forward end of the bucket is held in an elevated position: that is to say, in a partially open position so that as the dirt passes up between the lower edge 38 of the apron 37 and the blade 26, the dirt piling up in the bucket 27 can gravitate into the apron, after which the apron 37 can be moved to a closed position so as to retain the load. The apron is pivotally supported on side plates 25 by pivot pins 39. The load-retaining position is shown in Figure 1.

The reeving of the two control cables will now be described.

Rope 40 controls the first listed function, namely depth control, as in Mork. It passes, from a winch (not shown) over one of sheaves 41 on forward truck 21, and thence several times around sheaves 42 on bracket 43 and sheaves 44 on cross beam 32, finally being anchored to either. Bracket 43 is mounted on forward truck 21. Drawing-in on this rope 40 draws sheaves 42 and 44 together, thus raising the digging blade.

Rope 45, controls the fourth listed function, namely apron-opening. It passes, from the winch (not shown), over one of sheaves 41, and thence several times around sheaves 46 on bracket 47 and sheaves 48 on apron 37, finally being anchored to either. Bracket 47 is mounted on cross beam 32. Drawing-in on this rope 45 draws sheaves 46 and 48 together, thus raising the apron, as shown in Figure 3.

Interlock rope 49 controls the second-listed function, namely dumping. It passes from anchorage 50' on bracket 51' on one side of the main frame, then around spool or tilted sheave 52' on the end of cross beam 32 then back over sheave 53' on bracket 51', then (see Figure 4) down over the back surface of bucket 27 to and around a series of direction-changing sheaves 54', or other curved surface, thence up to take-up sheave 55 attached to the end of take-up bolt 59 which is mounted on the back of bucket 27, and then back along a similar path, on the opposite side of the scraper, over direction-changing sheaves 54'' or other curved surface, the back of bucket 27, sheave 53'' on bracket 51'', spool or tilted sheave 52'' on the other end of cross beam 32, and lastly to an anchorage on bracket 51''. The result of this reeving is that when the apron 37 is approximately half opened (i. e. just above open position for digging), one of sheaves 56 on each side of the apron will engage and deflect upwardly the lower reaches 57 of rope 49, and the tension thus imparted to rope 49 will raise bucket 27 slowly with great force (since only a short length of rope 49 is drawn in by this initial deflection). This large initial force is desirable to break the bucket from carry position in which it may be stuck when digging sticky material. Furthermore spreading of material dumped will be more uniform due to raising the bucket and apron at the same time. When the apron has been raised further to the position shown in Figure 2, another of sheaves 56 on each side of the apron will engage and start to deflect upwardly the upper reaches 58 of rope 49, with the result that rope 49 will now be drawn in and bucket 27 will be raised twice as fast as before. This high speed increases steadily with further deflection

of both reaches of rope until the apron is fully raised and the bucket is in full dumping position (see Figure 3).

Referring now to Figure 4, it will be noted that my take-up sheave 55 serves two purposes. First, it insures that equal lifting forces will be applied to each side of the bucket at all times, even when sheaves 56 on the apron deflect rope 49 more on one side of the scraper than on the other, due to warping of the apron or accumulation of dirt on the sheaves; and if the rope on one side should break, it insures that the rope on the other side will release the bucket. Second, it makes it possible to take-up or adjust the length of rope 49 by tightening or adjusting bolt 59, and thereby prevent any lag in dumping due to a slack rope and permit adjustment to the proper tension in carry position.

Turning now to my second embodiment, which is shown in Figure 5, we see this embodiment is the same as my first embodiment, except that rope 49 is now anchored to a lower point on the scraper main frame, as at apron pivot 39. The effect of this is to lower the position of lower reach 57 of rope 49, thereby causing the bucket to start dumping when the apron is more nearly closed. Thus the amount of opening of the apron before dumping starts can be varied for different types of digging by merely changing the anchorage to a different one of several alternative points which can be made available on a single machine.

Having now described and illustrated two forms of my invention, I wish it to be understood that my invention is not to be limited to the specific form or arrangement of parts herein described and shown.

When, in some of the claims, I refer to an "interlocking means" operatively connecting the bucket and apron, I intend thereby a means such that the motion of the actuated element (the bucket) is constrained or determined by the motion of the other element itself (the apron), rather than by the action of a common actuating means.

I claim:

1. In a carry-type earth-moving scraper, having ground supports, a main frame supported thereby in such manner as to be raisable and lowerable, a digging blade carried by the main frame, means to raise and lower the main frame and thereby the digging blade, a dirt-retaining bucket capable of being shifted to dump, a front apron capable of being shifted to dump, and means to shift the apron to dump; the combination therewith of interlocking means operatively connecting the bucket to the main frame and to the apron in such a way that whenever the apron is shifted beyond partial dumping position toward full dumping position, the apron will cause the interlocking means to dump the bucket, said interlocking means including two reaches of rope rigged on the main frame in such a manner that one reach is lengthened by the apron by shifting the apron for initial slow and forceful shifting of the bucket, and both reaches are so lengthened for later fast and less forceful shifting of the bucket.

2. A scraper according to claim 1, further characterized by the fact that the apron shifts the bucket to dump by upwardly deflecting one and then both of said reaches of rope.

3. In a carry-type earth-moving scraper, having ground supports, a main frame supported thereby in such manner as to be raisable and lowerable, a digging blade carried by the main

frame, means to raise and lower the main frame and thereby the digging blade, a dirt-retaining bucket pivoted on the main frame adjacent the blade and capable of being tilted forwardly and upwardly to dump, a front apron pivoted on the main frame and capable of being moved upwardly to dump, and means to thus move the apron to dump; the combination therewith of interlocking means operatively connecting the bucket to the main frame and to the apron in such a way that whenever the apron is shifted beyond partial dumping position toward full dumping position, the apron will cause the interlocking means to dump the bucket, said interlocking means including a plurality of vertically spaced reaches of rope extending from operative association with the bucket to a portion of the scraper with respect to which the apron is relatively movable during its upward dumping movement, and of means carried by the apron to successively engage these reaches as the apron is raised to dump.

4. In a carry-type earth-moving scraper, having ground supports, a main frame supported thereby in such manner as to be raisable and lowerable, a digging blade carried by the main frame, means to raise and lower the main frame

10
15

and thereby the digging blade, a dirt-retaining bucket capable of being shifted to dump, a front apron capable of being shifted to dump, and means to shift the apron to dump; the combination therewith of interlocking means operatively connecting the bucket to the main frame and to the apron in such a way that whenever the apron is shifted beyond partial dumping position toward full dumping position, the apron will cause the interlocking means to dump the bucket, said interlocking means including a plurality of vertically spaced reaches of rope so located on the main frame as to be successively engaged by the apron as the apron is shifted to dump.
